UNITED STATES PATENT OFFICE.

CHARLES ALMON BENNETT, OF DOVER, NEW JERSEY.

TYPE-WRITING MACHINE.

No. 888,457.

Specification of Letters Patent.

Patented May 26, 1908.

Application filed September 6, 1907. Serial No. 391,664.

To all whom it may concern:

Be it known that I, CHARLES ALMON BENNETT, a citizen of the United States, residing at Dover, county of Morris, and State of New Jersey, have invented certain new and useful Improvements in Type-Writing Machines, of which the following is a full, clear, and exact description.

This invention relates to typewriting machines.

Among the main objects is to provide a simple construction including many improvements in that type of a machine which is embraced in very small compass so that it may be conveniently transported but which nevertheless is so designed as to embody practically all the advantages of the larger, high priced, standard machines.

Many of the advantages which this machine affords will be understood upon reading the following description.

In the drawings, Figure 1 is a plan view of the machine complete; Fig. 2 is a plan view with certain parts removed and showing the remaining parts as they appear in their idle position; Fig. 3 is a similar view showing the position of the parts as they appear when a certain key has been depressed so as to project the type wheel into position to print a certain letter; Fig. 4 is a vertical cross-section through the center of the machine; Fig. 5 is a view of the under side of one bank of keys; Fig. 6 is a side elevation partly in section, of the parts shown in Fig. 5; Fig. 7 shows a single group of keys separated; Fig. 8 is a cross-section of the type-wheel and related parts, the section being in a plane at right angles to the section of Fig. 4.

a is a rectangular base-plate.

a' is a back-plate.

a² a² are end-plates.

a³ is a top-plate detachably secured at its ends to plates a².

b is the carriage slidable in a guide-way, formed in part by back-plate a' and rails a⁴.

b' is a roller-platen.

b¹ is a paper-guide.

b² is a scale.

b³ is a feed-rack.

b⁴ is a hand-wheel at one end of the roller b', while b⁵ is a ratchet-wheel at the other end thereof.

b⁶ is a finger-piece, having a suitable pawl to engage the ratchet-wheel for effecting a line space.

b⁷ is a paper holding spring-clip.

c is a reciprocating type-wheel carrier mounted to slide transversely of the frame a in suitable guide-ways c'.

c² is an arbor on slide c arranged to support pinion c³. With the assistance of said pinion the arbor also supports type-wheel c⁵.

c⁴ are pins on pinion c³ which cause the type-wheel to rotate with said pinion.

c⁶ is a cross-guide on slide c in turn carrying a⁵ a slideable stop-rack c⁷ meshing with pinion c³.

The type-wheel c⁵ is provided with circumferential rows of type, the upper row furnishing lower-case letters; the central row capital letters, and the lower row figures and miscellaneous characters. Suitable shift mechanism for raising the type wheel c⁵ to present the desired row consists of a rock shaft f, having crank-arms f', f². The arm f' projects under type-wheel c⁵, while the arm f² is supported by the forward end of a tilting lever f³, which has two finger-pieces f⁴ and f⁵ so arranged that when the latter is depressed the type-wheel will be lifted half way and when the former is depressed the type-wheel will be lifted to its highest operative position.

g is an oscillator pivoted at x on slide c and in the form of a three-armed lever, the long arm having a segmental rack g' meshing at all times with pinion c³.

g², g³ are the short arms and these normally bear on the block w. At two different points away from the pivot x each short arm g² is provided with link connections of unique construction.

g⁴ is a link pivoted at g¹.

g⁵ is one part of a toggle link pivoted at g⁶ to the oscillator. As shown the point g⁶ is farther from axis x of the oscillator than the point g⁷, and these three points are arranged out of line.

g⁷ is the second member of the toggle link, the same being pivoted to the base a.

g⁸ is a link pivoted about midway in the toggle link member g⁵.

g⁹ is a bridging beam connecting the links g⁴ and g⁸.

g¹⁰ is a spring-pressed lever pivoted at g¹¹, and engaging the bridging beam g⁹, or some part of the linkage on one side of the machine.

g¹² is an equalizer beam pivoted midway of its length to a suitable part of the frame, so as to have a rocking movement.

g¹³ is the spring which operates the beam g¹⁰, and linkage, said spring being connected at one end to one end of the beam g¹², while at

its other end it bears in one of several notches in the beam g^{10} . By shifting the position of the latter end of the spring from one notch to another, the pressure upon the lever g^{10} may 5 be varied.

Having described the system of linkage on one side of the machine, it is to be understood that a corresponding system is provided on the opposite side, so that through the medium of 10 the beam g^{12} an equalizing effect is produced. Both springs g^{13} always contribute an equal share of work so that the pressure required to operate similarly located keys on opposite sides of the machine will be uniform.

15 h is a spring-pressed pawl, the free end of which will engage with the feed rack b^4 at the under side of the carriage in such a manner that upon each forward movement of the slide c , the platen-carriage will be pushed to 20 the left one step for word or letter spacing.

The key-board of the machine may be said to be made up of two banks, located on opposite sides of the oscillator. A description of the keys on one side will be sufficient.

25 k is a pivotal support carried by suitable bearing lugs, depending from the plate a^2 .

The key levers are divided into banks and each bank into relatively subordinate groups with the members of each group arranged in 30 line extending depth-wise of the machine. The key-levers of one group are best seen in Fig. 7.

k' represents a key-piece arm.

35 k^2 is a bell crank extending downwardly below the pintle bearing k .

Each key is provided with a suitable lifting spring k^3 . The key-piece arms k' in each group are of unequal length, so that the finger pieces may lie directly in front of one another. These finger pieces, with the exception of the outermost, overstand the underlying key piece arms so that when one of the inner key pieces is depressed, those key-piece arms underlying the same, will also be depressed. One of the key pieces of each group is provided with an offset clip k^4 , presenting an inclined face arranged to receive the notched rear edges of the bell-crank extensions of the other key pieces in the same group. The function of said clip is to cause the bell crank extensions k^2 of each group to rest snugly against one another when operating conjointly or dependently.

40 p is the space key. p' is a stop at the underside to limit its downward movement. The space key rests upon one or more of the adjacent key arms, so that through the bell crank extension of such key arm, the space key may affect the movement of the slide c , 45 as, and for the purpose, hereinafter described. One of the bell crank extensions k^2 of each group of keys is longer than the others. There are notches in the front edge of each of the bridging beams g^6 of a number 50 corresponding to and facing up with the

longer bell crank arms of the key groups. When a key is depressed the longer bell crank arm of its particular group will engage in its respective notch in bridging beam g^6 . If that notch be midway in said beam, the force 70 of the blow on the key will be transferred to the short arm of the oscillator, partly through link g^3 and partly through links g^8 and g^6 . If the engagement with the beam g^6 be nearest the link g^3 , the major portion of the force will 75 be transferred through said link. If the contact with the beam g^6 be in a notch nearer the link g^8 , the major part of the force will be transferred to the oscillator through the link g^8 and toggle link g^6 . The end keys of the 80 key board are those which operate through the toggle-links last referred to, and since the major part of the force applied thereby is transmitted to the extreme end of the short arm g^2 greater leverage is secured. By this 85 system of linkage, corresponding keys on opposite sides of the key board require not only a uniform pressure, but all the keys on one side of the key board may be operated by substantially the same pressure, or stroke. 90

I have not attempted to show the particular location of the characters upon the keys or type wheel. It is sufficient to say that any key-board arrangement may be employed. The location of the characters on the type wheel is such that those characters which require the greatest rotation of the type wheel in order to bring them into printing position, are those characters which appear on the keys most removed from the center of the machine. This arrangement is employed because, when one of the keys most remote from the center is struck, the type wheel is operated mainly through the medium of the toggle lever system, which is connected with the extreme end of the short arm where the greatest leverage is availed of. It is because these outer keys have more difficult work to perform, that this toggle arrangement has been devised. By this toggle 100 arrangement a greater throw to the actuator is secured by the same stroke and depression given to any and all keys. The type wheel is actuated with positiveness and certainty no matter what key is struck, so long as a 105 substantially uniform force or stroke is employed.

The so-called bell crank extension of each of the key levers acts as a stop for the purpose of checking the movement of the rack 110 c' . So long as the rack is permitted to move the type wheel will rotate, but the instant it is stopped it will present one type thereon in proper position for printing, thus these bell crank extensions operate as selectors. Now, 115 when the rack encounters one of these stops it is obvious that the further rotation of the pinion c^3 is checked, consequently any further depression of the key will cause the oscillator and the associated parts, including 120

the type wheel to make a forward movement bringing the particular type selected into contact with the paper on the platen.

5 *r, r* are inking rolls respectively mounted in spring frames which cause said rolls to bear against the type face of the type wheel when the latter is advanced and rotated, thereby inking all of said type faces.

10 *s* is a type wheel centering pin which faces up in front of the type wheel, so that when the latter is advanced the pin will enter a perforation (not shown) in the peripheral wall of the type-wheel adjacent to the selected type, thereby absolutely centering the same. This centering pin *s* is preferably mounted upon a stiff spring frame. Two of these centering pins may be employed, one to center the type wheel when in the lower and middle positions, the other to center the 15 wheel when in the upper position.

20 *t* is a bell to warn the operator at the proper time that the end of the line is about reached. *t'* is the hammer therefor, *t²* is an operating crank arm engaged by a projection 25 on the carriage, which momentarily lifts and then releases the same.

30 *u* is a spring retainer for the type-wheel, the same being pivotally mounted on an upright *u'*, in two bearings spaced apart. Between these bearings the shank of the retainer has an offset bend as shown in Fig. 8, so that the upper end will assume either one of the two positions shown.

When it is desired to secure a word space, 35 the space-key *p* is depressed thus advancing slide *c* by pawl *h* to a sufficient degree to force the carriage ahead one step. The stop *p'* will check the space key early enough to prevent the type wheel from striking the 40 platen.

The construction is exceedingly compact as shown by the fact that the drawings are full size. Nearly all of the parts may be made by simple and inexpensive processes so 45 that the cost of the machine is very small. By the arrangement of the keys in groups, the same are subordinated to each other for independent action or for cumulative or dependent action.

50 The linkage arrangement, though simple, is exceedingly effective, not only in the respects already enumerated, but also because by said arrangement that short arm of the oscillator which is serving as the fulcrum during operation is held to its seat *w* by the same springs that return the key levers to their normal position when finger pressure thereon is removed. The seat *w* is provided with a double incline highest in the 55 center, and each incline serves as a bearing or seat for that short arm *q²* which normally rests thereon. These two bearings furnish a broad support which centers the oscillator effectively when in its idle position.

60 In order to avoid confusion, I shall refer,

in the claims, to the link *g³* as a "simple link", and to the link *g⁶* as a "toggle link"

What I claim is:

1. In combination, a rotary type carrier, an oscillator coöperating therewith, means for stopping the rotation of the said carrier at predetermined points, a sliding support for said parts and means for operating said parts, including a toggle link 70

2. In combination, a rotary type carrier, an oscillator coöperating therewith, means for stopping the rotation of said carrier at predetermined points, a sliding support for said parts and means for operating said parts, including a toggle link and a simple 75

80 link. 3. In combination, a rotary type carrier, an oscillator coöperating therewith, means for stopping the rotation of said carrier at predetermined points, a sliding support for said parts, means for operating said parts, including a toggle link and a simple link, and a bridging beam connecting said two links. 85

4. In combination, a rotary type carrier, an oscillator coöperating therewith, means for stopping the rotation of said carrier at predetermined points, a sliding support for said parts, means for operating said parts, including a toggle link, a bridging beam connecting said two links, and a series of key 90 levers including bell-crank extensions, said bell-crank extensions being arranged side by side and substantially parallel with said bridging beam. 95

5. In combination, a rotary type carrier, means for rotating the same about its own axis and moving it laterally, said means including two banks of keys and link connections, and springs for each set of link connections to restore them to normal position, 100 and a rocking equalizer lever operatively connected with said springs. 105

6. In combination, a rotary type carrier, means for rotating the same about its own axis and moving it laterally, said means including two banks of keys and link connections, springs for each set of link connections to restore them to normal position, 110 a rocking equalizer lever operatively connected with said springs, and means for varying the spring tension between said rocking equalizer beam and said linkage. 115

7. In a type writer, a type wheel, means for rotating the same on its own axis and moving it laterally, including an oscillator and a stop rack, said oscillator and stop rack moving bodily with said type wheel, a lever arm extension from said oscillator, and two separate link systems connected with said lever arm at different points from the axis of the oscillator, a bridging beam connecting said link systems, and a key lever arranged to coöperate with said bridging beam and with said stop rack. 120

8. In a type writer, in combination, a 125

130

- rotary type wheel, an oscillator therefor, a single means for rocking said oscillator and stopping the rotation of said type wheel at predetermined points and moving said type 5 wheel laterally, and means intermediate said operating means and said oscillator, including two sets of links connected at different points away from the axis of the oscillator, one of said links being of the toggle type.
- 10 9. In a type writer, a type wheel, means for rotating the same on its own axis and moving it laterally, including an oscillator and a stop rack, said oscillator and stop rack moving bodily with said type wheel, a lever 15 arm extension from said oscillator, two separate link systems connected with said lever, a bridging beam connecting said link systems, and a key lever arranged to coöperate with said bridging beam and with said stop rack.
- 20 10. In a type writer, a type wheel, means for rotating the same on its own axis and moving it laterally, including an oscillator and a stop rack, said oscillator and stop rack moving bodily with said type wheel, a lever arm 25 extension from said oscillator, two separate link systems connected with said lever, one system including a toggle lever, a bridging beam connecting said link systems, and a key lever arranged to coöperate with said 30 bridging beam and with said stop rack.
11. In a type writer, in combination, a rotary type wheel, an oscillator therefor, operating means for rocking said oscillator and stopping the rotation of said type wheel 35 at predetermined points and moving said

type wheel laterally, said means including two sets of links connected at different points away from the axis of the oscillator.

12. In a type writer, a group of key levers of different lengths relatively subordinated 40 to each other for dependent or independent action, said key levers having bell crank extensions, and a laterally extending clip carried by the longest key lever of each group and arranged to engage another key 45 lever of the same group when the latter is depressed.

13. In a type writer, a group of key levers of different lengths relatively subordinated 50 to each other for dependent or independent action, said key levers having bell crank extensions, and a laterally extending clip carried by the bell crank extension of the longest key lever and arranged to engage the bell crank extension of another key lever 55 when the latter is depressed.

14. In a type writer, a group of two or more key levers of different lengths relatively subordinated to each other for dependent or independent action, said key levers each 60 having a bell crank extension, a laterally extending clip carried by one bell crank extension arranged to engage the other bell crank extension when said levers are moved dependently.
